INDEPENDENT SCREW CLOSURE

Joseph Andrew Burns, Toronto, Ontario, Canada

Application October 30, 1935, Serial No. 47,344
In Canada October 19, 1934

5 Claims. (Cl. 221—60)

My invention relates to improvements in closures for containers such as bottles or collapsible tubes and more particularly to a closure which has a cover pivoted on one side of the neck of the container in order to swing transversely over the dispensing orifice.

In this class of closure it is usual to provide a means on the cover to engage the member carrying the pivotal connection so as to provide an 10 interfitting connection in the form of a claw or the like that is engaged by the closing of the cover.

The object of the present invention is to provide a closure with a base which pivotally carries 15 the cover and has a threaded bore for screwing onto the neck of the container so that the base may be utilized to hold the cover in its closed position. This is accomplished by mounting the base on the neck portion in such a manner that 20 it has a partial turning movement sufficient to cause the neck to abut the cover when turned in a screw-on direction.

A distinctive advantage of this construction is that the cover can be held in an open position by 25 turning the base relative to the neck so as to cause the neck to protrude slightly therethrough in order to act as a stop. The cover is preferably provided with a seat such as a cork insert or the like for engagement by the neck of the container with a view to making an air-tight closure.

Referring to the accompanying drawing:

Figure 1 is a plan view of the invention applied to the threaded neck of a collapsible tube.

Figure 2 is a side elevation depicting the cover 35 of the closure in its closed position.

Figure 3 is a plan view similar to Figure 1, but showing the cover swung open.

Figure 4 is a sectional view through the closure and neck portion of the container. In this view 40 the cover is shown closed.

Figure 5 is a similar sectional view but showing the cover open.

In the accompanying drawing, the invention is shown in its application to a collapsible tube which is generally indicated by the reference numeral 6 and has an externally threaded neck 7. The base 8 surrounds the neck and has an internally threaded bore by which it is mounted on the neck so that upon being turned it will be fed 45 axially according to the direction of rotation. In order to prevent the base from being unscrewed from the neck it is preferable to provide a shoulder or other expediency that will act as a stop to limit the turning movement. This may be accomplished by providing the base with a counter-

bore or recess 8' and upsetting the outer extremity of the neck as at 8" so as to engage the counterbore or recess. The base is preferably of an oval shape as shown and the cover 9 is also of an oval shape, the cover being pivoted at 10 5 to the base at one side of the neck. It is preferable to embody the pivotal member in the cover so that it will extend from its underface only and not be seen from its outerface. The pivotal member may be upset as customary in order to 10 form a shoulder to secure the cover to the base in a swivel relation. The base is provided with a groove 10' diametrically opposite the pivot of the cover for engagement with a tongue 11 carried by the cover. The groove preferably terminates in a shoulder 10" that acts as a stop for the cover when it is in its closed position, but the tongue and groove are so positioned that they will interfit as the cover is swung to its closed position.

20 A sealing member 12, such as a cork disc or the like, is lodged in a recess in the cover for abutting engagement with the neck of the container. According to this construction the cover can be locked in its closed position by giving the base 25 a partial turning movement in relation to the neck of the container sufficient to bring the neck in abutting engagement with the sealing member 12. It has been found in actual practice that by making the threads of a suitable pitch 30 a half turn of the base is sufficient to secure the cover. To release the cover the base is turned in a screw-off direction which releases the neck from engagement with the seat. This enables the cover to be swung transversely of the base to 35 its open position.

What I claim is:—

1. The combination with the neck of a container, of a closure comprising a base having a bore therethrough by which it is turnably mounted on said neck, interfitting means on the neck and bore whereby the base is moved axially of the neck upon being turned, a cover pivoted to the base at one side of the neck and swingable transversely over the neck orifice, interfitting means 40 carried by the cover and the base at the other side of the neck such that binding pressure is applied thereon by turning the base and cover as a unit to cause the neck to engage the cover.

2. In a closure for a container having a dispensing mouth encompassed by a threaded neck, a base encircling the neck and engaged therewith by a threaded bore, a cover pivoted to the base eccentrically of the neck and swingable 45 transversely over the dispensing mouth, and 50

means carried by the base and the cover to interfit as the cover is swung to a closed position in which the cover is retainable by turning the base to cause the neck to abut the underface of the cover.

5. In a closure for a container having a dispensing mouth encompassed by a threaded neck, a base encircling the neck and engaged therewith by a threaded bore, a cover pivoted to the 10 base eccentrically of the neck and swingable transversely over the dispensing mouth, a sealing seat carried by the cover for engaging the neck, and means carried by the base and the cover to interfit as the cover is swung to a closed 15 position in which the cover is retainable by turning the base to cause the neck to abut said seat.

4. In a closure for a container having a dispensing mouth encompassed by a threaded neck, a base encircling the neck and engaged therewith 20 by a threaded bore, a cover pivoted to the base eccentrically of the neck and swingable transversely over the dispensing mouth, a tongue carried by the cover at an angle to the neck axis

and remotely of the pivotal axis of the cover, a groove formed in the base and disposed to engage said tongue as the cover is swung to a closed position in which the cover is retainable by turning the base to cause the neck to abut an underface of the cover.

5. A closure for a collapsible tube or other container having a dispensing orifice encompassed by an externally threaded neck, said closure comprising a base encircling said neck and having a 10 threaded bore extending completely through it threadedly engaged with the neck, a cover shiftably mounted on the base and constrained for movement only in a plane at right angles to the neck axis and disposed thereby to close and open 15 said orifice according to its position, and interlocking means on said base and said cover whereby the cover is retainable over the orifice by turning the base in a screw-on direction sufficient to feed the neck into wedging abutment 20 with the cover.

JOSEPH ANDREW BURNS.
